William N. Moore,

By *James M. Carter* Attest.

UNITED STATES PATENT OFFICE.

WILLIAM N. MOORE, OF JOLIET, ILLINOIS.

COOKING-STOVE.

SPECIFICATION forming part of Letters Patent No. 708,062, dated September 2, 1902.

Application filed April 21, 1902. Serial No. 103,840. (No model.)

To all whom it may concern:

Be it known that I, WILLIAM N. MOORE, a citizen of the United States, residing at Joliet, in the county of Will and State of Illinois, 5 have invented certain new and useful Improvements in Cooking-Stoves, of which the following is a specification.

This invention relates to improvements in cooking stoves or ranges, and more particularly in the construction and arrangement of the key-plate thereof, or, in other words, of that section of the stove-top which overlies the fire-box and carries the griddles or covers immediately above the fire. The invention 10 contemplates the pivoting of such key-plate at one edge, so that it may be swung up to expose the fire for broiling or toasting or to enable the fire to be more readily raked, replenished, or rekindled.

20 To this end the invention consists in the matters hereinafter set forth, and particularly pointed out in the appended claim, and will be fully understood from the following description of the construction illustrated in 25 the accompanying drawings, in which—

Figure 1 is a perspective view of the front end of a cooking stove or range provided with a hinged or swinging key-plate in accordance with the present improvement. Fig. 2 is a 30 vertical sectional view better showing the manner in which said key-plate is supported in its raised position. Fig. 3 is a top plan detail of the plate itself.

In said drawings, A designates a cooking 35 stove or range the structural details of which, except in the particulars hereinafter mentioned, are not of importance herein and need not be particularly described. A' designates the top of said stove or range, A² its upper 40 framework, which rises above the top A² in a familiar manner to support a warming oven or shelf, as the case may be, and B is the rectangular key-plate, which covers the fire-pot and supports the covers or griddles B', 45 that lie immediately above the fire. Said key-plate is made bodily removable after the manner commonly employed in structures of this character and is also provided at one edge with pivot-pintles b, upon which the 50 key-plate may be swung open, as upon a hinge. (See Fig. 2.) As herein shown, these pivot-pintles b are located at the inner edge

of the key-plate or that most remote from the adjacent end of the stove, and the swinging movement of the plate will be upwardly and 55 inwardly, as shown in said Fig. 2, so as to render the fire readily accessible from said end. To support it in this raised position, the rear outer corner of the plate is attached to a suspender C, which depends from the adjacent 60 side bracket of the back frame A² of the stove. This suspender consists in this instance of a flexible cable or chain, which is carried over a pulley D on the inner face of the side bracket a of said back frame. The inner end of this chain 65 is secured to a projecting ear d on the outer rear corner of the key-plate, and its outer end, which is carried through an aperture a' in the side bracket adjacent to the pulley D, is provided with a handle c, which may be 70 hooked under a projection a² on the outer face of said bracket to hold the key-plate up. When the key-plate is down or closed flush with the top of the stove, this handle c will be raised nearly to the aperture a', as shown 75 in Fig. 1; but it is only necessary to seize the handle, draw it down, and pass it under the projecting hook a² in order to swing the key-plate open, as in Fig. 2, and hold it indefinitely in this position. This will uncover the 80 entire fire-pot and greatly facilitate those cooking operations, such as toasting or broiling, which demand direct exposure to the fire. It will also greatly facilitate building of the fire, as well as the raking or replenishing of a fire already built. A little strap or 85 ledge a³ of the stove-top is provided to inclose the rear pintle b of the key-plate and prevent the latter from being pulled up out of place when the plate is lifted by the chain C, as 90 described.

It will of course be obvious that the chain C may be replaced by a flexible metallic cable or the like and with the same result and that various other changes may be made in the 95 details of the construction shown without departure from the spirit of the invention claimed.

It will be observed that by the arrangement shown the suspender and its attaching lug b' 100 will be out of the way of the cooking vessels, thereby practically eliminating all danger of the suspending-chain and said lug being injured by the heavier kinds of cooking vessels.

It will also be seen that by attaching the lifting device to the rear outer corner of the key-plate it will be necessary to employ but one keeper or strap to hold the pintles in place
5 and that that one will be located at the back of the stove, where it will be out of the way in case it is desired, for the purposes of strength and economy, to have it project above the surface of the stove-top.

10 I claim as my invention—

A stove having a back frame and a side bracket at its rear and also a key-plate in its top, adjacent to said bracket, said key-plate being pivotally connected at its inner edge to
15 the stove-top, so that it will swing upwardly

and inwardly, a lifting and suspending device connected to the rear outer corner of the key-plate, adjacent to said side bracket, and extending upward and connected to said side bracket, and means for locking said suspending device when the key-plate is lifted. 20

In testimony that I claim the foregoing as my invention I affix my signature, in presence of two subscribing witnesses, this 29th day of March, A. D. 1902.

WILLIAM N. MOORE.
